UNITED STATES PATENT OFFICE.

AMASA ST. ONGE AND CLEMENTS A. BROWN, OF PROVIDENCE, RHODE ISLAND.

GRID FOR COTTON-PICKER MACHINES.

No. 866,284.

Specification of Letters Patent.

Patented Sept. 17, 1907.

Application filed May 14, 1906. Serial No. 316,891.

To all whom it may concern:

Be it known that we, AMASA ST. ONGE and CLEMENTS A. BROWN, citizens of the United States, residing at the city of Providence, in the county of Providence and 5 State of Rhode Island, have invented certain new and useful Improvements in Grids for Cotton-Picker Machines, of which the following is a specification.

This invention relates to grids for cotton picker machines, and consists of the novel construction, combination and arrangement of parts, as hereinafter described and claimed.

The objects of our invention are to provide loosely mounted blades of peculiar shape for grids for such machines and to adjust such blades simultaneously to 15 a greater or less degree of aperture, at will.

In the accompanying drawings like reference numerals indicate like parts.

Figure 1 is a fragmentary vertical sectional view of a portion of a cotton picker machine, including the 20 beater, the feed-rolls, the apron and a grid constructed according to our invention. Fig. 2 is a fragmentary view of a portion of our improved grid, showing in full lines and in dotted lines, respectively, the two positions of the blades and also illustrates the form of said 25 blades. Fig. 3 is a view, partly in section and partly in side elevation showing the blades in one of their adjusted positions, together with the means of moving and adjusting said blades. Fig. 4 is a similar view showing the blades and adjusting means in another 30 position. Fig. 5 is a cross-sectional detail view, as seen on section line 5.—5. of Fig. 4.

In the drawings only so much and such parts of a cotton picker machine are illustrated as relates to the mounting and operation of the improved mechanism 35 constituting our invention.

In the drawings 1 represents the beater of the usual form, mounted on a shaft 2. The beater and shaft revolve in the direction of the arrow A. Two feed rolls 3, 3, are in the usual position and are operated in the 40 usual manner, and deliver the cotton to the action of the beater.

The usual apron 4 is arranged below the beater 1, and the grid, which constitutes our invention, is disposed between the end of the apron 4 and the feed 45 rolls 3, 3.

The grid has two oppositely arranged parallel side pieces, plates or castings 5, which extend longitudinally on the frame of the machine. Each side plate 5 has two downwardly extending brackets 6 and 7, which 50 have holes therein to allow bolts 8 and 9, respectively, to pass through said brackets into the frame of the machine, to support said side plates in position. Each side plate 5 is curved, as shown, the upper curvature and lower curvature being parallel with each other, 55 and both concentric with the shaft 2.

The upper ends of the side plates 5, adjacent to the

brackets 6, are placed just below the lower feed roll 3, as illustrated in Fig. 1. Each side plate 5, on the exposed face thereof, at the outer edge, has a longitudinally extending flange 10, which flange is also extended 60 around both ends of said side plate and is formed into a terminal horizontal lug 11. A set screw 12 passes through a tapped hole in the lug 11 and secures the end of the apron 4 in position against a block 13.

On each side plate 5, on the exposed face thereof, 65 is cast or secured a series of stationary lugs 14, arranged in a curved line, parallel to the upper and lower edges of said side plate. Each lug 14 is in the form, in cross section, of a truncated isosceles triangle, the truncated apex thereof being directed downwardly. These lugs 70 14 are spaced at equal distances apart.

A curved notched plate 15 has a series of teeth 16, each of which teeth has equally beveled longitudinal sides, as shown. The notched plate 15 has feet 17, by which it is supported slidably on the upper edge of the 75 flange 10, adjacent to the lower edge of the side plate 5.

A bolt 18 extends down from the central foot or flange 17 of each notched plate 15, through a slot 19 in the flange 10 of the side plate 5. A nut 20, engageable with the bolt 18, serves, when tightened up on the 80 bolt 18, to hold the notched plate 15 in any position to which it is adjustably set. A washer 21 is interposed between the nut 20 and the flange 10 to aid the said nut to get a frictional hold against said flange. The extent of the slot 19 determines the limit of the 85 movement of the notched plate 15 in such adjustment.

The blades 22, which constitute the grate bars or grid, are arranged in series between the fixed lugs 14 and have their lower ends (which are rounded) seated in the notches, which are formed between the teeth 90 16 of the notched plate 15. These blades 22, which are shown in cross-section in the several figures of the drawing, extend across the machine from side to side, and rest on the notched plates 15, 15.

As seen in Figs. 1, 3 and 4, but most plainly in Fig. 95 2, on an enlarged scale, each plate 22 consists of a straight body portion, having a lower rounded edge 23, and on the upper bent end 24, substantially diamond-shaped in cross-section, terminating in a sharp whipping edge 25. As seen in Fig. 2, when the blades 22 100 are in the position shown in full lines, they are farther apart than when they are in the position shown in dotted lines, such difference in position being caused by the sliding movement of the notched plates 15 at the opposite ends of said blades, respectively. The blades 105 22 can, by means of adjusting the notched plates 15, 15, be made to assume any degree of angular direction within the limits allowed by the position of the bolt 18 in the slot 19 on each side of the machine.

A flange 26 on the upper edge of each side plate 5 110 (see Fig. 5) prevents the blades 22 from rising above the plates.

By examination of Figs. 3 and 4 and on comparison of them, it is seen that the whipping edges 25 of the blades 22 are always the same distance apart, whether said blades are in their open or closed positions, or in some 5 intermediate position; but the apertures or clearances between the blades, through which space the motes, seeds and other dislodged matter fall by gravity, are much wider when the blades stand in their open space position shown in Fig. 3, than when in their closed position shown in Fig. 4. By the adjustment of the blades, by means of the sliding notched plates 15, 15, such spaces of the blades apart give a narrow or broad clearance for this purpose, to any desired degree within the limits 10 already described. This angularity of the blow upon 15 the cotton with respect to the position of the whipping edges of the blades gives the requisite degree of bluntness or sharpness to the stroke of the beater upon the cotton fibers for the purpose of cleaning them according to their grade or length of staple.

20 It is evident upon study of Fig. 2, that the blades 22, in moving from the position shown in solid lines to the position shown in dotted lines (or vice versa), necessarily slide along the top angular edge of the adjacent lug 14, and at the same time rock on their rounded 25 lower edges, to a small extent, which are seated loosely in the spaces between the teeth 16 of the notched plates 15, 15.

When the upper or whipping edge of each blade 22 is in the open position shown in Fig. 3, said whipping 30 edge is more nearly at a right angle with the end of the beater 1, but when the blade is in the closed position seen in Fig. 4 said edge is at an acute angle with the end of the beater.

As seen in Fig. 2, when the blades 22 are in their 35 open position, shown therein by full lines, the right-hand corner or edge of the diamond-shaped head 24 of the blade is in the same horizontal plane with the left-hand corner or edge of the diamond-shaped head of the next blade adjacent toward the right; but when the 40 said blades are in their closed position, shown in said figure by dotted lines, the right-hand corner or edge of the diamond-shaped head of one of the blades is considerably lower than the left-hand corner or edge of the diamond-shaped head of said next adjacent blade, so 45 that the aperture or clearance between said two contiguous blades in a vertical line is much diminished.

As usual in such machines, the air-currents (caused by a fan, not shown), which pass up between the blades

22 and serve to lift and carry the cleaned cotton over and along the top of the blades, such cotton being in a 50 loose, light, fluffy sheet, the dislodged motes, seeds, and foreign substances, falling through the space between the plates, which, if the blade or bar were triangular in cross-section, as usual, might be carried upward by the air currents, are prevented from thus moving by means of the shoulder on each blade formed by the lower right-hand face of the diamond-shaped head 55 24 of the blade, and so are enabled to fall entirely through the grid into a proper receptacle.

We claim as a novel and useful invention and desire 60 to secure by Letters-Patent:—

1. The improved grid for cotton picker machines herein described, consisting of the combination of the two curved side plates, each having a lateral flange projecting from the lower edge thereof; means for supporting said side 65 plates in position; a plurality of stationary, equi-spaced lugs in series upon each side plate, which are substantially triangular in cross-section, with the bases thereof constituting their upper edges, respectively; a curved notched plate slidably mounted on said flange of each 70 side plate and provided with beveled teeth; and a series of blades each loosely mounted between said stationary lugs in abutment therewith respectively and adapted to have a longitudinal sliding movement thereon to a limited extent, each of which blades has a rounded bottom and is 75 seated thereby in corresponding spaces between the teeth of the notched plates, respectively.

2. In a device of the character described, the combination of two curved side plates arranged parallel and opposite to each other; a curved notched plate supported 80 on each side plate and movable thereon; fixed, triangular, equi-spaced lugs in the curved row on each of said plates; and a plurality of separate blades mounted only at their bottom ends loosely between corresponding teeth of said notched plates so as to have a limited oscillation thereon and extending up loosely between said fixed lugs. 85

3. In a device of the character described, the combination of two curved side plates, each having a curved row of triangular, equi-spaced, integral lugs; a curved notched-plate supported on each side plate and movable thereon; and a plurality of separate grid-bars, each having an upper, sharp and forwardly-directed edge, and each loosely resting on its bottom edge between corresponding teeth of the notched-plates, and extending upwardly, at an acute angle, loosely between corresponding lugs of said side 90 plates, and supported laterally by said lugs. 95

In testimony whereof we affix our signatures in presence of two witnesses.
